UNITED STATES PATENT OFFICE

2,426,700

BOOT WITH EXPANSIBLE TOP

Assad M. Malluk, New York, N. Y.

Application January 6, 1943, Serial No. 471,421

1 Claim. (Cl. 36—4)

1.

This invention relates to foot covering, and more particularly to a type of boot adapted to protect the wearer from the elements and to insure the wearer against passage of water, sand, insects or any foreign matter into the foot or leg.

A further object is to provide a covering for the leg portion of a boot to prevent the seepage of water through the flexible portions, seams and closures thereof.

Since, in waterproof boots of all types, a certain amount of moisture, condensation, perspiration and other sources, is apt to collect within the boot, and particularly within the foot portion thereof, it is desirable that the foot portion should be readily accessible when the boot is removed so that the interior thereof may be easily cleaned, dried and inspected.

A further object of this invention is to provide a boot which has these features and which may be opened up so that not only may the interior of the foot portion be thoroughly cleaned and dried, but to enable the removal of any foreign matter whatsoever.

With these and other objects in view, reference is had to the accompanying drawings, in which—

Fig. 1 is a perspective view of the boot partly opened up;

Fig. 2 is a view of the boot in closed position with its supplemental legging partly broken away to show its relationship to the boot;

Fig. 3 is a perspective view of the supplemental legging;

Fig. 4 is a view in slightly smaller scale of a foot covering adapted to be used with the legging shown in Fig. 3;

Fig. 5 is a view of the top portion of the boot in its closed position and with the supplemental legging removed.

The boot 10 consists of a foot portion 11 having a sole 12 and heel 13 which may be either stitched or cemented to the foot portion 11 in such manner as to make a waterproof connection. The upper or leg portion 14 consists of a series of sections 15, 16, 17 and 18. It will be readily appreciated that while I have shown four sections, 15 to 18, inclusive, any convenient number may be used. It will be further appreciated that these sections are considerably wider at the top than at the bottom in order to allow the leg to properly fit and to be opened wide so as to expose the inner portion of the shoe at the heel and shank. The sections are joined together by seams 19, 20, 21 and 22, which may be either stitched or cemented together. It will be appreciated that

2.

these sections may be made of either rubber or leather, or combinations thereof, without departing from the scope of my invention. It will also be appreciated that, while I have shown a perspective view of the boot in open position in Fig. 1, it may be opened to a considerably greater extent to expose the inner portion of the foot. It will be seen from Fig. 1 that the leg portion 14 is so widely flared at the top that it normally flares outwardly and droops downwardly to a normally wide open position.

In fitting the leg of the boot to the wearer, it is folded at points 25, 26, 27, 28, 29, 30, 31 and 32 so that the points 25 and 26 come to one side 15 of the boot on the outside, and points 29 and 30 come to the other side of the boot on the outside, and points 27 and 28 come together at one side of the boot on the inside and points 21 and 28 come together at the opposite side on the inside. 20 Adjacent points 25 and 26, and 29 and 30 are series of fasteners 35 and 36, of any suitable type. While I have shown buckles of the tongue and link type, having a tongue 37 and a link 38, any type of fastener may be used. Due to 25 the flexibility and construction of the leg member, it is possible to remove the boot and replace it for ordinary purposes by merely loosening either of the sets of fastening members 35 or 36, leaving the other set fastened.

30 In order to further protect the leg, I have provided a rubber legging member 40 which is adapted to be pulled over the leg of the wearer. The legging member 40 may be of any desired height, extending, if preferred, to the thigh, or 35 terminating at the top of the boot. The boot 10 is provided with a bead 41 placed at the lower portion thereof, and a second bead 42 may, if desired, be positioned adjacent the top of the boot. The legging 40 should be made of an elastic material, such as rubber, and is provided with a lower reinforcement 43, grooved on its inner side to cooperate with and be removably secured to the bead 41. A similar reinforcement 44 may be provided at the top of the legging, defining a 40 groove 45 adapted to grip and engage the bead 42. Above the reinforcement 44 the legging may be further reinforced at 46 and provided with an inwardly extending rim or lip 47 to extend over the top of the boot and to grip the leg of the wearer 50 snugly, thus preventing the passage of any water or other materials downwardly into the top of the boot.

While the boot 10 may be worn with or without the legging, it is obvious that the legging gives 55 added protection, not only to the wearer, but to

the boot itself. It will also be appreciated that my legging 40 may be worn with other types of boots or may be added to a high shoe directly over the clothing. If desired, pull-on tabs 50 may be affixed to the top of the legging to facilitate its use.

The foot covering shown in Fig. 4 is designed to cooperate with the legging shown in Fig. 3 and to form a complete covering for the foot or, in fact, for a boot. The foot covering consists of an overshoe of rubber or similar material 55 which is adapted to extend up to the area of the ankle. It is provided with a reinforced top 56 forming a bead which engages the groove 43 of the legging, thus making a complete covering which may be worn over the boot shown in Fig. 1, or any other boot, or which, if desired, may be worn over an ordinary shoe. Both the bead 56 and the groove 43, being elastic, tend to grip the leg of the wearer tightly to form a waterproof connection. A tab 57 may be supplied to aid the wearer in putting on the shoe covering portion.

I claim:

A boot having a leg portion made of a plurality of sections a flexible material secured together at their overlapping margins, said sections being wider at the top than at the bottom thereof, and being adapted to be folded together into four pair of folds, one of said pair of folds being at the

front and inside of the leg, another of said pair of folds being at the rear and inside of the leg, the others of said pairs of folds being at the front and rear and outside of the leg, and fastening elements joining the folds at the sides of the leg.

Certificate of Correction

Patent No. 2,426,700.

September 2, 1947.

ASSAD M. MALLUK

It is hereby certified that error appears in the printed specification of the above numbered patent requiring correction as follows: Column 3, line 25, after the word "sections" insert *of*; and that the said Letters Patent should be read with this correction therein that the same may conform to the record of the case in the Patent Office.

Signed and sealed this 11th day of November, A. D. 1947.
